[57] CLAIM

The ornamental design for a telephone unit, substantially as shown and described.

DESCRIPTION

FIG. 1 is a top plan view of a telephone unit, showing our new design;

FIG. 2 is a bottom plan view thereof;

FIG. 3 is a front elevational view thereof;

FIG. 4 is a rear elevational view thereof;

FIG. 5 is a side elevational view thereof taken from the right side of FIG. 1; and

FIG. 6 is a side elevational view thereof taken from the left side of FIG. 1.

A portion of the cord shown in broken lines in the above figures is so represented for facility of illustration.

FIG. 1

FIG. 2

FIG. 3

FIG. 4

FIG. 5

FIG. 6
